UNITED STATES PATENT OFFICE.

EDWIN E. SLICK, OF JOHNSTOWN, PENNSYLVANIA.

METHOD OF MAKING RETURN L'S.

1,426,324.

Specification of Letters Patent. Patented Aug. 15, 1922.

Application filed September 26, 1919. Serial No. 326,624.

To all whom it may concern:

Be it known that I, EDWIN E. SLICK, a citizen of the United States, residing at Johnstown, in the county of Cambria and State of Pennsylvania, have invented a new and useful Improvement in Methods of Making Return L's, of which the following is a full, clear, and exact description, reference being had to the accompanying drawings, 10 forming part of this specification, in which:—

Figure 1 is a section through the V-shaped metal blank from which the return L is made;

15 Figure 2 is a section of said blank after its legs are pierced;

Figure 3 is a section showing the bending of the legs;

20 Figure 4 is a similar section through the completed L; and

Figure 5 is a bottom plan view.

The present invention relates to return L's and method of making. By return L's are meant the U-shaped pipe fittings into which 25 two pipes are secured to get a reversal of direction. In forming the return L a V-shaped blank 2 is first forged. The blank 2 has two solid legs 3 and 4 of circular cross section which come together to form the nose 5 of 30 the V. The legs of this V-shaped forging 2 are pierced, preferably by a round nosed drill, so as to form the openings 6 and 7 which meet at 8 in the point of the V. The drilled legs 3 and 4 are then bent into parallelism, as shown in Figure 3. This may be 35 done in any suitable way, preferably by bringing the drilled blank to a proper heat and then bending the legs 3 and 4 by mandrels and dies. After the legs 3 and 4 are

bent parallel they are internally threaded, 40 as shown in Figure 4, to form the completed L. If the L is to be used on unthreaded pipe the legs need not be threaded.

The return L is entirely seamless, has maximum strength and is made by simple 45 operations.

The present invention is not limited to its 50 illustrated details but may be otherwise embodied within the scope of the following claims:

I claim:

1. The method of making return L's, which consists in forming a V-shaped blank, piercing the legs of the V-shaped blank to form a V-shaped passage therethrough, and 55 bending the legs of the V parallel, substantially as described.

2. The method of making return L's, which consists in forging a solid V-shaped metal blank, piercing the legs of the V to 60 form a V-shaped passage therethrough, and then bending the legs of the V parallel, substantially as described.

3. The method of making return L's, which consists in forging a solid V-shaped 65 metal blank, drilling the legs of the blank to form a V-shaped passage therethrough, and then bending the legs of the blank parallel, substantially as described.

4. The method of making return L's, 70 which consists in forming intersecting holes in a solid blank of metal and thereafter bending the mouth portions of said holes parallel, substantially as described.

In testimony whereof, I have hereunto set 75 my hand.

EDWIN E. SLICK.
